UNITED STATES PATENT OFFICE.

ALBERT H. SCHMIDT, OF DETROIT, MICHIGAN.

METHOD AND APPARATUS FOR DRYING AND STRETCHING SKINS.

1,320,100.

Specification of Letters Patent. Patented Oct. 28, 1919.

Application filed January 25, 1919. Serial No. 273,015.

To all whom it may concern:

Be it known that I, ALBERT H. SCHMIDT, a citizen of the United States of America, residing at Detroit, in the county of Wayne 5 and State of Michigan, have invented certain new and useful Improvements in Method and Apparatus for Drying and Stretching Skins, of which the following is a specification, reference being had therein 10 to the accompanying drawings.

The invention relates to the art of tanning hides and skins for leather purposes, but has more particular reference to the drying and stretching of skins of small animals, 15 such for instance as sheep skins, goat skins and calf skins.

In the present state of the art various constructions of drying frames have been employed in the drying and stretching of 20 leather, which may be generally classified in two types. In the one type the entire skin is arranged in a plane and is stretched by nailing or otherwise securing the opposite edge portions to relatively movable members. In the other type the center of the 25 skin is drawn around a bar so as to bring the sides into parallel planes, the edges of said sides being nailed or clamped to a member which is relatively movable to the bar.

With both types of apparatus as heretofore 30 constructed the stretching is laterally of the skin and is applied to the sides to fully as great an extent as it is applied to the center. This is objectionable, inasmuch as the center 35 of the skin, or the portion adjacent to the backbone of the animal is much thicker than the portions at the sides. Consequently where the tension is uniform there is a tendency for the side portions to stretch to a 40 greater extent than the center. Thus, to equalize the thickness it is frequently necessary to shave the central portion. A further objection to the type of apparatus in which the skin is drawn around a bar is that the 45 pressure of said bar against the skin will leave a mark after the skin is dry.

My invention involves a new method in 50 which the lateral tension on the skin is concentrated at the central portion, or portion of greatest thickness, while the side portions are to a great extent relieved from tension. This results in the stretching out of 55 said central portion, increasing the total width of the skin and decreasing the thickness at the center, so that shaving in many

instances is unnecessary. A further feature of my improvement is the application of the lateral tension differentially at the opposite ends of the skin. This provides for stretching the neck portion to a greater extent than 60 any other portion, which is desirable, as this is the portion of greatest thickness and also for the reason that it contains fat wrinkles which may be drawn out.

My invention also consists in a simple 65 form of apparatus by which the drying and stretching may be effected. This comprises a holding frame having mounted therein a pair of relatively movable panels, the flanks or belly portions of the skin being marginally nailed to the respective panels and the nails extending along the ends as well as at the side edges but not across the center or ends of the back portion of the skin. After nailing, the panels may be forced apart by 70 wedges or equivalent means, which applies the tension on the central portion of the skin between the panels and permits of stretching the neck end to a greater extent than the rear end. The fact that the nails 75 extend around the end edges of the skin relieves the side portions from tension, thereby avoiding overstressing or the drawing of the latter too thin.

The specific construction of apparatus is 80 fully illustrated in the drawings, in which—

Figure 1 is a side elevation of the stretching frame showing a skin nailed thereto and the wedges driven in to place the skin under tension;

Fig. 2 is a side elevation, showing a stack or row of frames as arranged for drying;

Fig. 3 is a perspective view of a frame with a skin thereon after the removal of the wedges, showing the degree to which the 90 skin has been stretched at the center.

In detail A and B are parallel side bars which are connected preferably by pairs of parallel end bars C and D to form a rectangular frame. E and F are panel members, each being preferably formed of several boards slightly spaced from each other and connected together at their ends by cleats G. The panels are slidably secured between the pairs of end bars C and D, and the cleats G are arranged outside of said end bars and operate as stops or guides to prevent disengagement. H and I are wedges adapted for insertion between the panels E and F at opposite ends of the frame, one 100 105 110

of the panels, such as F, being beveled at J and J' to correspond to the inclination of the wedge.

A frame constructed as above described is 5 exceedingly simple and inexpensive, being formed from straight strips which may be quickly nailed together.

In use the skin is placed across the two panels E and F with the center of the back 10 panels in the line of division between said panels. The skin is then nailed around this margin, as indicated at K; after which the frame may be reversed and another skin may be similarly nailed to the opposite sides of the 15 panels. The wedges H and I are then driven in to place both skins under tension; after which the frames may be stacked, as indicated in Fig. 2. It will be noted that the pairs of end bars C and D space the 20 frames from each other so as to leave a sufficient air space between the skins for proper drying. Also the panels E and F being formed of a plurality of boards spaced from each other will permit of cross circulation of 25 the air and access to all parts of the skin.

During the drying process the wedges H and I may be tightened from time to time, as may be necessary to properly stretch the 30 central portion of the skin, and the wedge H, which separates the portions of the panels 35 to which the neck of the skin is attached, may be driven to a greater degree than the wedge I. Thus the thick skin will be stretched out and thinned and also most of the fat wrinkles will be straightened out.

After the drying is completed the wedges 40 may be released and, as shown in Fig. 3, the central portion of the skin will be considerably increased in width. The skins may then be removed and the frames used again for other work.

While I have described a specific construction of apparatus, it is obvious that it can be modified without departing from the 45 spirit of my invention. As for instance, other means for separating the panels may be substituted for the wedges H and I. However, I find the wedges to be very satisfactory, both on account of simplicity in 50 construction and for the reason that the operator may walk along the row and by tapping on the ends of the wedges tension the skins as required. The operator will soon acquire sufficient skill to determine just 55 what force should be applied to the wedge to effect the stretching without danger of overstraining or tearing.

What I claim as my invention is:—

1. In a process for drying and stretching 60 skins, the step of applying lateral tension to the central portion of the skin or portion adjacent to the back bone, which is in excess of the tension applied to the flank or belly portions thereof.

65 2. In a process for drying and stretching

skins, the step of stretching the central portion of the skin or portion adjacent to the back bone to a greater extent than the flank or belly portions thereof.

3. The process of drying and stretching 70 skins, comprising the marginal securing of the opposite flank or belly portions of the skin to separable members, and the separation of said members to stretch the central portion of the skin or portion adjacent to 75 the back bone.

4. The process of drying and stretching 80 skins, comprising the securing of the opposite flank or belly portions of the skin with the margin of each portion at the side and 85 end thereof relatively fixed, and the separation of the two portions to effect stretching and thinning of the central portion of the skin or portion adjacent to the back bone, said portion being free at its ends.

5. The process of drying and stretching 90 skins, comprising the nailing of the flank or belly portions on opposite sides of the center of the skin marginally at side and ends thereof to separate panels, and forcing 95 said panels apart to stretch the central or back portion of the skin which is unattached at its ends.

6. The process of drying and stretching 95 skins, comprising the mounting of a pair of skins on opposite sides of a pair of panels with the center or back portion of each skin adjacent to the line of division between the panels and at sides and ends thereof, marginally nailing the portions of each skin 100 upon opposite sides of the center to the respective panels, and forcing the panels apart to simultaneously stretch the central portion of each skin.

7. An apparatus for stretching skins, 105 comprising a pair of relatively movable panels adapted for the marginally nailing at side and ends of the respective flank or belly portion of a skin on opposite sides of the central or back portion thereof, a frame 110 in which said panels are slidably mounted, and means for forcing said panels apart.

8. An apparatus for stretching skins comprising a pair of panels adapted for the marginally nailing at side and ends of the 115 flank or belly portions of a skin upon opposite sides of the center or back portion thereof, a frame in which said panels are slidably secured, and means for forcing said panels apart differentially at opposite ends.

9. An apparatus for stretching skins, comprising a pair of adjacent panels adapted for the mounting respectively of the portions of a skin on opposite sides of the center thereof, a frame in which said panels are slidably secured, and wedges adapted to be driven between the panels at opposite ends thereof to force the same apart.

10. An apparatus for stretching skins, comprising a frame formed of side bars and 130

5 pairs of spaced end bars connecting said side bars, panels extending across said frame slidable between the spaced end bars, and means for forcing said panels apart at opposite ends thereof.

11. An apparatus for stretching skins, comprising a frame formed of side bars and pairs of spaced end bars, panels each comprising a plurality of spaced boards extending across said frame and between the spaced end bars, and cleats for securing the boards of the same panel arranged outside of said end bars.

12. An apparatus for stretching skins, comprising a frame formed of side bars and pairs of spaced end bars, panels extending

across said frame, each comprising a plurality of spaced boards extending through the space between said end bars, cleats parallel to and outside of said end bars securing 20 the boards of the same panel to each other, and wedges adapted to be driven between the end bars to force said panels apart.

13. An apparatus for stretching skins, comprising a frame formed of side bars and 25 pairs of spaced end bars, panels extending across said frame between the spaced end bars and in the plane of said side bars, and wedges adapted to be driven between said end bars to force said panels apart.

15 In testimony whereof I affix my signature.

ALBERT H. SCHMIDT.
